United States Patent Office.

L. M. REED, OF TROY, OHIO.

Letters Patent No. 85,534, dated January 5, 1869.

IMPROVEMENT IN SAP-SPILES.

The Schedule referred to in these Letters Patent and making part of the same.

To all whom it may concern:

Be it known that I, L. M. REED, of Troy, in the county of Geauga, State of Ohio, have invented certain new and useful Improvements in Sap-Spouts; and I do hereby declare that the following is a full and complete description of the same, reference being had to the accompanying drawings, making a part of this specification, in which—

Figure 1 is a side view of the spout.

Figure 2, an end view.

Like letters of reference refer to like parts in the several views.

The nature of this invention relates to a metallic sap-spout, consisting of a tube constituting the spout, and a spike, whereby the spout is secured to the tree.

In fig. 1, A is the spout, which is a short tube made of sheet-metal.

B is the spike, a detached view of which is shown in Figure 3.

The shank of said spike is triangular or three-sided, two sides being slightly curved, as shown in fig. 2.

The extreme end of the spike is provided with a spur, a, whereas the opposite end is provided with a hook, C, the purpose of which will be presently shown.

D is a collar, which, when the spike is inserted in the tube, fits the bore, thereby filling the same as a kind of partition or diaphragm.

The hooked end of said spike is inserted in the tube by slightly raising the spur-end, until the hook reaches a slot in the tube, into which it is forced by depressing the end. The hook will now project through the side of the tube, as seen in fig. 1, and is therein fixed by soldering.

The practical operation of this spout is as follows:

A hole, a trifle larger than the diameter of the tube, is bored into the tree, in which the spike is gently driven, together with a short length of the end of the spout, which will fit tight therein, and thereby prevent the sap from flowing out around the spout.

In consequence of the peculiar angular character of the spike, it does not fill the hole, hence the sap will not be checked from flowing, but will find its way out to the end of the tube through the small hole c, cut in the lower edge of the diaphragm.

To the inserted spout the sap-bucket is hung behind the hook C, and is therefore prevented from slipping off. The weight of the bucket, as it draws down upon the spout, forces the spur a into the wood, which will prevent the spout from being pulled out by the weight of the bucket.

This spout fully prevents the sap from souring around the tube, by the exclusion of air from the hole, and is therefore well adapted to this purpose.

It is strong, durable, and easily inserted in the tree, requiring no more skill and care than an ordinary wooden one.

What I claim as my invention, and desire to secure by Letters Patent, is—

The herein-described spout, consisting of the spike B and tube A, combined in the manner as and for the purpose set forth, as a new article of manufacture.

L. M. REED.
